(57) **CLAIM**

I claim the ornamental design for a full offset-circular aperture can, as shown and described.

DESCRIPTION

This application is related by subject matter to co-pending U.S. application Ser. No. 12/797,171 filed Jun. 9, 2010, U.S. application Ser. No. 29/363,492 filed Jun. 10, 2010, U.S. application Ser. No. 29/363,498 filed Jun. 10, 2010, U.S. application Ser. No. 29/363,500 filed Jun. 10, 2010, and U.S. application Ser. No. 29/363,502 filed Jun. 10, 2010. This application is also related by subject matter to co-pending applications U.S. patent application Ser. No. 29/368,323, filed Aug. 23, 2010 entitled “Full Longitudinally Oriented Oval Aperture Can” and U.S. patent application Ser. No. 29/368,324, filed Aug. 23, 2010 entitled “Full Transversely Oriented Oval Aperture Can.”

FIG. 1 is a top perspective view of an full offset-circular aperture can according to our new design;

FIG. 2 is a side view thereof, with all sides being the same;

FIG. 3 a top plan view thereof; and,

FIG. 4 is bottom plan view thereof.

The portions of the drawings appearing in broken line are for environment only and do not form a part of the claimed design.
